UNITED STATES PATENT OFFICE

MAURICE N. PRANGE, OF DETROIT, MICHIGAN, ASSIGNOR TO ELLEN MAY PRANGE, OF DETROIT, MICHIGAN

HONE

Application filed November 7, 1927, Serial No. 231,730. Renewed July 21, 1932.

This invention relates to hones for lapping tools and has as an object to improve generally and render more efficient devices of this character.

5 An object of this invention is to provide a lapping tool in which all danger of binding of the stones or blades will be obviated and by which a smooth and even grinding may be accomplished.

10 A further object of this invention is to provide means for accurately adjusting the grinding stones, the said means being operable to adjust the stones either inwardly or outwardly.

15 A still further object of this invention is to provide means for compensating for wear in the adjusting mechanism so that a positive adjustment of the stones will always be assured.

20 Another object of this invention is to provide a detachable driving connection for the hone, which connection will, however, be simple in construction and thoroughly efficient in operation.

25 Other objects and advantages of the invention will become apparent as the following description proceeds particularly when reference is had to the accompanying drawings wherein;

30 Figure 1 is a side elevational view of a hone or lapping tool constructed in accordance with my invention;

Figure 2 is a longitudinal sectional view 35 through the device shown in Figure 1;

Figure 3 is a sectional view taken on the line 3—3 of Figure 2;

Figure 4 is a sectional view taken on the line 4—4 of Figure 2;

Figure 5 is a sectional view taken on the 40 line 5—5 of Figure 3;

Figure 6 is an end elevational view of the device with certain parts removed, and

Figure 7 is a perspective view of the stone holder forming a part of the device.

45 Referring now particularly to the drawings wherein like reference characters designate corresponding parts throughout all views of the same, the reference character A designates the cage of the lapping tool, B the stone holder and C the driving collar therefor.

The cage A is a unitary structure preferably a single casting and includes the upper head 10, the lower head 11 and the ribs 12 connecting the upper and lower heads. As clearly illustrated in Figure 4 of the drawings, the ribs 12 are spaced circumferentially of the heads and are preferably triangular in cross section. The head 10 is provided with a circumferential flange 13 apertured as at 55 14 for a purpose hereinafter to be described and is further provided with a centrally arranged boss 15 provided with an opening 16 to form a bearing for the shaft of the adjusting mechanism also hereinafter to be described. The head 10 is also provided with 60 a plurality of radially extending slots or channels 17.

The lower head 11 of the cage is similar to the upper head 10 in that it is provided with a circumferentially arranged flange 18, the central boss 19 and the radially-extending slots 20 which are arranged in alignment with the slots 17 formed in the upper head 10. The boss 19 is also provided with 65 an opening 21 similar to the boss of the 70 upper head.

Adapted to be adjustably carried by the cage A are the stone holders B. As clearly illustrated in Figure 7 of the drawings, these 75 stone holders comprise trough-shaped members 22 provided with side walls 23 and 24. While both of these walls slope outwardly from the base of the stone holder it will be noted that the wall 23 is arranged at a more obtuse angle to the base of the stone holder 80 than is the wall 24 and that the wall 23 is provided with a plurality of bearing surfaces 25. The other wall 24 is provided on its outer periphery with a plurality of ribs 26 85 provided with threaded openings 27 for the reception of adjusting screws 28. Arranged within the stone holder B is a stone 29 adapted to have one face clamped against the bearing surfaces 25 by means of the adjusting screws 28. For preventing cracking of 90 the stone 29 by the adjusting screws 28 and for effecting tighter clamping of the stone 29 I provide a bowed plate 30 adapted to engage the free side of the stone and adapted 95 to be forced against the stone by the said 100

screws 28. It will thus be seen that by virtue of the slope of the wall 23 and also therefore of the bearing portions 25 the stone 29 will be supported in the stone holder at an angle to the median plane of the holder.

For the purpose of adjustably supporting the holders B within the cage there is provided at opposite ends of each holder B flanges 31. These flanges are provided on their outer free edges with teeth 32 and are adapted to be slidably received in the channels or slots 17 and 20 as clearly illustrated in Figure 2 of the drawings. By reference to Figure 2 of the drawings it will be noted that the teeth 32 are inclined at one side only and that their inner faces are straight or arranged at right angles to the plane of the flanges. This constitutes an important feature of my construction since by virtue of this arrangement of the teeth and the co-operation of these teeth with the adjusting means hereinafter to be described, an accurate adjustment of the stone holders is assured. It will also be noted particularly by reference to Figure 1, that the flanges 31 are arranged to one side of the median plane of the holder so that the median plane of the holder does not coincide with the radial planes of the cage. It is by virtue of this feature, together with the arrangement of the stone within the holder that I am able to preclude the possibility of the stones binding when the lapping tool is being used.

For adjusting the stone holders radially of the cage there is provided upper and lower scrolls 33 and 34 respectively, these scrolls being arranged adjacent the upper and lower heads of the cage as clearly illustrated in Figure 2 of the drawings. The upper scroll 33 has a bearing as at 35 on the outer end of the boss 10 and is also provided on its outer face with a centrally arranged boss 36 grooved as at 37. Spiral teeth 38 arranged on the inner face of the scroll 33 are adapted to mesh with the teeth 32 of the flanges on the upper ends of the stone holders so that the rotation of the scroll 33 tends to move the said stone holders outwardly or inwardly. As clearly illustrated in Figure 2 of the drawings, the spiral teeth 38 are also provided with one vertical face which engages the vertical faces of the teeth 32 whereby, as brought out before, an accurate and positive adjustment of the stone holders is assured.

Lower scroll 34 is similar in structure to the upper scroll 33 in that it is provided with a bearing 39 on the boss 19 of the lower head. The lower scroll is also provided with the teeth 40 adapted to mesh with the teeth 32 formed on the flanges on the lower ends of the stone holders and it is to be noted that these teeth are also provided with one vertical face. The lower scroll is further provided on its outer face with a boss 41 grooved as at 42.

For transmitting the rotative movement of the upper scroll 33 to the lower scroll 34, there is provided a shaft 43 which projects through the openings 16 and 21 in the upper and lower heads respectively, and through a central opening 44 in the upper scroll 33 and a central opening 45 in the lower scroll 34. The shaft 43 is provided on its upper end with transversely extending pins or projections 46 adapted to be received in the groove 37 in the boss 36. The lower end of the shaft 43 is threaded as at 47 and is provided adjacent its threaded portion with a transverse opening 48 adapted to receive a pin 49 which engages in the groove 42 in the boss 41. It will thus be seen that by virtue of the projections 46 and the pin 49 rotative movement of the upper scroll 33 will be transmitted to the lower scroll 34.

For drawing the lower scroll 34 closer to the upper scroll 33, there is provided a disk 50 threadedly engaging the threaded end 47 of the shaft 43. The disk 50 is provided with a boss 51 having a plurality of radial grooves 52 and a pin 53 is adapted to be inserted through the end of the shaft 43 and to seat in selected ones of these grooves. It will thus be seen that by removing the pin 53 the disk 50 may be tightened on the shaft 43 to force the scrolls 33 and 34 into firmer mesh with the teeth on the flanges 31 and that after the disk 50 is so tightened, it may be locked in its tightened position by the pin 53. Further it will be seen that by drawing the scrolls closer together compensation may be made for any wear on the teeth of the scrolls 33 and 34 and the teeth on the flanges 31.

Mounted on the upper end of the cage A is the driving collar C. This driving collar is provided with a reduced end portion 54 adapted to be received within the flange 13 formed on the upper head 10 and is adapted to be held in assembled position by suitable threaded members 55 extending through the openings 14 formed in the flange 13.

The walls of the driving collar C is provided at two diametrically opposite points with thickened portions 56 and 57 respectively and extending through one of these thickened portions there is arranged the means for imparting rotary motion to the upper scroll 33. This means includes a shaft 58 journaled in the thickened portion 56 and provided at its inner end with a pinion 59 adapted to mesh with teeth 60 formed on a boss 61 carried by the upper scroll 33. The outer end of the shaft 58 is provided with a head 62 for engagement with a suitable adjusting tool.

Obviously, adjustment of the stone holders is accomplished by rotation of the shaft 58 which is transmitted through the pinion 59 and teeth 60 to the scrolls 33 and 34. As brought out before, rotation of the scrolls 33

and 34 radially moves the stone holders by engagement with the teeth 32.

For driving the lapping tool there is provided a shank driver 63 having a flattened head 64 arranged at one end and a threaded socket 65 arranged at its other end for engagement with the threaded end of a suitable driving shaft 66. Pivotally secured to the flattened head 64 of the drive shank as by 10 a pin 67 is a double yoke-like member 68 terminating at its opposite ends in pintles 69. These pintles are adapted to engage in the driving collar C for transmitting the rotation of the shaft 66 to the lapping tool.

For providing a detachable connection between the pintles 69 and the drive collar C, the drive collar is provided on its inner periphery with segmental circumferentially arranged flanges 70 and 71. As clearly illustrated in Figure 5 of the drawings the flange 70 extends from the thickened portion 57 to a point spaced from the thickened portion 56 so as to form an entrance channel 72 while the flange 71 extends from the thickened portion 56 to a point spaced from the thickened portion 57 to provide the entrance channel or passage 73. Secured to the base of the adjusting collar C is an annular ring 74 which forms a flange projecting inwardly of the wall of the adjusting collar, this flange cooperating with the flanges 70 and 71 to form channels 75 and 76 within the adjusting collar C. To connect the yoke 68 to the drive collar the pintles 69 are passed through the passages 72 and 73 into the channels 75 and 76 respectively and the yoke is then turned until the pintles 69 are moved within the channels 75 and 76 to positions adjacent the thickened portions 56 and 57. For preventing movement of the pintles 69 out of the channels 75 and 76 suitable pins 77 are detachably mounted in openings 78 formed in the flanges 70 and 71, these pins extending across the channels 75 and 76 as will be readily apparent.

In operation the lapping tool is adapted to be inserted within a cylinder and rotated to cause the stones 29 to grind the walls of the cylinder. By virtue of the arrangement of the stones 29 at an angle to the median plane of the holders C and by virtue also of the offset positions of the flanges 31, on the holders C, the stones 29 will be carried at an angle 55 to the radial planes of the cage A and will thereby engage the walls of the cylinder in such a manner as to be incapable of binding. While I have shown and described one form which my invention may assume, it is to be 60 understood that this disclosure is for the purpose of illustration only and is not to be construed as definitive of the limits of my inventive idea. I therefore reserve the right to make such changes in the details of construction and arrangement of parts as will fall

within the purview of the accompanying claims.

What I claim as my invention is:

1. In a lapping tool, a cage, a stone holder carried by said cage, a stone within said holder, and means for clamping said stone within said holder at an angle to the median plane thereof, said means including a resilient plate arranged within the said holder and at one side of the said stone, and a threaded member carried by the said holder and engaging the said plate. 70

2. In a lapping tool, a trough-like stone holder having a side wall sloping outwardly from its base, a stone within said holder, a bowed plate arranged adjacent one side of said stone and members carried by said holder and engaging said plate to force said stone against the sloping side wall of said holder. 80

3. In a lapping tool, a cage provided with a radial channel, a stone holder, and a flange formed on said holder to one side of the longitudinal median plane thereof, for engagement in the said channel. 85

4. In a hone, a cage having upper and lower heads, each of said heads being provided with a radially extending channel, a stone holder, and a flange on each end of the said stone holder, the said flanges being adapted for engagement in the said channels and being arranged to one side of the longitudinal median plane of said holder. 90

5. In a hone, a cage having a head and a radially extending channel in said head, a stone holder and a flange on said holder arranged to one side of the longitudinal median plane of said holder, said flange being engageable in said channel for mounting said stone holder on said cage with its median plane angularly arranged with respect to the radial planes of said cage. 100

6. In a lapping tool, a cage, stone holders carried by said cage, and means for adjusting said stone holders radially of said cage, said means including a scroll at one end of said cage, a shaft having a pinion on one end for driving said scroll, a head on the other end of said shaft for engagement by a turning tool, a second scroll, and means for driving said second scroll from said first mentioned scroll, said means including a shaft arranged centrally of said cage, transverse pins carried by said shaft for engagement with said scrolls, and means carried by said shaft for varying the spaced relation of said scrolls on said shaft. 110

7. In a lapping tool, a stone holder, a stone within said holder, and means including a bowed resilient plate engageable with one side of said stone for clamping said stone against a wall of said holder. 115

8. In a lapping tool, a cage, a head for said cage, said head having a radially extending channel, a stone holder, and a flange on said stone holder engageable in said channel, said 120

flange being arranged to one side of the longitudinal median plane of said holder whereby said holder is angularly positioned relative to the radial planes of said cage.

9. In a lapping tool, a tool holder having spaced side walls, a stone within the holder, and means including a resilient member interposed between one of the side walls aforesaid and the stone for clamping the latter against the other of said side walls.

10. In testimony whereof I affix my signature.

MAURICE N. PRANGE.
